E. GERMER.
STOVE.
FILED APR. 9, 1921.

UNITED STATES PATENT OFFICE.

EDWARD GERMER, OF ERIE, PENNSYLVANIA.

STOVE.

Application filed April 9, 1921. Serial No. 459,868.

To all whom it may concern:

Be it known that I, EDWARD GERMER, a citizen of the United States, residing at Erie, in the county of Erie and State of Pennsylvania, have invented new and useful Improvements in Stoves, of which the following is a specification.

Stoves having ovens which are heated from a gas burner are usually so formed as to expose the burner to air movements incident to opening and closing the oven door. Where the door is closed abruptly the draft is apt to extinguish the flame at the burner. The present invention is designed to obviate this difficulty.

The invention is illustrated in the accompanying drawings as follows:

Fig. 1 shows a central longitudinal section through the stove.

20 Fig. 2 a section on the line 2—2 in Fig. 1. Fig. 3 a plan view of the gas burner.

Fig. 1 marks the top of the stove, 2 the bottom of the stove, 3—the end walls and 4 the side walls, 5 the fire box. The oven is formed with the top wall 6, bottom wall 7, end wall 8 adjacent to the fire box and an opposite end wall 9. The rear wall of the sides 4 forms the rear wall of the oven. The oven walls are distanced from the walls 1, 3 and 2 so as to form a flue 10 through which gases pass, the gases being discharged by way of an opening 11 to the usual pipe flue (not shown). A burner tube 12 extends from the bottom of the oven to the bottom wall 2, the bottom of the tube being in communication through an opening 2^a with the atmosphere. The upper end of the tube opens into the oven. A burner 13 is arranged in the tube 12 and is supplied from a mixing pipe 14 leading to without the stove wall. The mixing pipe has the mixer 15 supplied with fuel from a jet 16. The burner is of the spider variety having the main jet openings 17. I provide a well 18 at the center of the burner, the upper end of the well having a contracted opening 19. Jets 20 lead to the bottom of this well. This well is closed against draft therethrough as shown.

The oven is provided with the usual door

22 as shown hinged at the bottom and has 50 the dampered outlet 23 when used as a gas oven. It will be understood that the oven may be used in connection with the fire box with an ordinary wood or coal fire and with the gas burner when desired.

55 By forming a protected burner closed against the draft therethrough a draft created by the closing of the door will not extinguish the flame from the jets 18. This flame will normally bottom in the opening 60 19 but when subjected to draft the well with the downward pressure prevents a movement of the cold air past the jet sufficient to reduce it below the ignition point. Consequently if the main-jets are all extinguished 65 they are immediately re-lighted from the protected pilot.

What I claim as new is:—

1. In a stove, the combination of an oven; a door on the oven; a main burner for the oven having an air passage to the oven for supplying air for combustion to the burner; and a protected burner having its jets arranged in a well closed against air draft therethrough and adapted to maintain ignition of the main burner.

70 2. In a stove, the combination of an oven; a door on the oven; a main burner for the oven having an air passage to the oven for supplying air for combustion to the burner; and a protected burner having its jets arranged in a well adapted to maintain ignition of the main burner, said protected burner being formed in the walls of the main burner and receiving its supply of combustible mixture from the main burner.

80 3. In a stove, the combination of an oven; a door on the oven; a main burner for the oven having an air passage to the oven for supplying air for combustion to the burner; and a protected burner having its jets arranged in a well adapted to maintain ignition of the main burner, said well having a contracted opening and being closed against air draft therethrough.

85 In testimony whereof I have hereunto set my hand.

EDWARD GERMER.
